STERILIZING TOOTHBRUSH RECEPTACLE

Milton T. Hanke, Chicago, Ill., assignor to
Margaret C. Blume, Chicago, Ill.

Application October 26, 1934, Serial No. 750,672

6 Claims. (Cl. 206—15.1)

This invention relates to a sterilizing container which also permits the drying of moist articles placed therein.

More specifically this invention relates to a tooth brush receptacle which sterilizes the brush and permits the evaporation of moisture from the brush.

Tooth brush holders have heretofore been either formed of non-pervious materials or have been provided with foraminous portions to permit a drying of the brush. Containers have also been provided with removable caps having compartments for disinfectants disposed therein to sterilize the container and brush. However, the use of impervious materials for tooth brush containers is not satisfactory because the tooth brush cannot dry when placed in such a container and soon becomes soggy and ineffective. The provision of foraminous portions in the container to permit a drying of the brush is also unsatisfactory because dirt and germs from the surrounding atmosphere can readily pass into the container.

I have now provided a sterilizing container for tooth brushes which also permits the evaporation of moisture from the brush without permitting ingress of dirt or germs. According to this invention, the tooth brush container is formed of a porous material such as unglazed porcelain or alundum. The interior of the walls of the container are impregnated with an antiseptic material for creating a sterilizing zone around the tooth brush.

It is, therefore, an object of this invention to provide a sterilizing receptacle which permits the drying of materials inserted therein.

A further object of this invention is to provide a moisture permeable receptacle for tooth brushes and the like which does not allow the ingress of dirt from the outside atmosphere.

A further object of this invention is to provide a tooth brush receptacle which sterilizes the brush and permits the same to dry therein while sealing the brush from contact with the outside atmosphere.

A specific object of this invention is to provide a porous tooth brush receptacle capable of creating a sterilizing atmosphere around the tooth brush.

Other and further objects of this invention will be apparent from the following description and annexed sheet of drawings which form a part of this disclosure.

On the drawing:

Figure 1 is an elevational view of a preferred

type of tooth brush holder according to this invention.

Figure 2 is a cross sectional view taken substantially along the line II—II of Figure 1.

Figure 3 is an enlarged fragmentary cross sectional view taken substantially along the line III—III of Figure 1.

Figure 4 is an enlarged fragmentary wall portion of a container, according to this invention, showing an alternative manner for disposing 10 antiseptic material within the container.

As shown on the drawing:

In Figure 1, the reference numeral 10 indicates generally a tubular container of a ceramic material such as unglazed porcelain, clay or other 15 porous material, provided with a bottom 11 and an open top adapted to receive a cover or closure member 12. The tube 10 may be formed with one or more flat faces 13 extending longitudinally thereof and with a peripheral groove 14. 20

The surface of the container 10 may be partly coated with a non-porous material such as a lacquer or a glazing material 15. The coating 15, however, is omitted from the flat portions 13 and the walls of the groove 14 so that moisture 25 may pass freely through these wall portions of the container.

As shown in Figure 2, the container 10 is sufficiently long to receive the entire length of a tooth brush. The brush 16 is inserted in the 30 container with the bristles 17 at the bottom thereof.

The cap 12 may be threaded into the open top of the container as indicated at 18. It should be understood, however, that any type of closure member such as a friction cap may be used in place of the threaded cap 12. 35

The groove 14 is positioned slightly above the level of the bristles 17 when the brush 16 rests against the bottom 11 of the container. Moisture from the bristles 17 can thus readily pass through the porous walls of the container 10. It should be understood, however, that the non-porous coating 15 may be dispensed with so that the entire outside surface of the container will be effective in the transfer of moisture to the atmosphere. However, it is preferred to use the coating 15 and to provide limited areas of unglazed portions such as 13 and 14 to present a 40 more attractive outside surface for the container. The groove 14 and the flat surface 13 present sufficient area to permit the evaporation of water from a tooth brush within eight hours' time. Since a tooth brush is seldom used in in- 45

ervals of less than eight hours, the container always delivers a dried brush.

As shown in Figure 3, the walls of the porcelain container are impregnated with an anti-septic material 19. Liquid or solid antiseptics may be used provided they have a vapor pressure sufficiently low to prevent too rapid dissipation from the walls of the container. Impregnation of the container walls with solid antiseptics may be accomplished by dissolving the antiseptic in a volatile solvent and impregnating the walls with the solution. The solvent then evaporates and leaves the solid antiseptic distributed in the porous walls. Likewise, the antiseptic may be melted and poured into the walls of the container and allowed to solidify and remain in the walls. Also other types of antiseptic may be sublimed and the sublimation vapors caused to impregnate the walls of the tube. Antiseptics such as menthol, chloretone, thymol, chlor thymol, para formaldehyde, dichloramine and ammonium bicarbonate have been used for impregnating the walls of the tooth brush container. Para formaldehyde and ammonium bicarbonate gives a complete sterilization of the brush. Para formaldehyde is effective because it evolves formaldehyde vapor. Since para formaldehyde is a solid, it retains its effectiveness for great lengths of time. In Figure 4, I have shown an alternative method for providing an antiseptic material on the inside of the container 10. As shown in Figure 4, the walls of the container 10 are coated on the inside with a paste or coating 20. The coating 20 is porous in nature and moisture readily penetrates therethrough to the porous container walls. Thus the antiseptic may be coated onto the inside walls of the container or impregnated into these walls. From the above description, it is evident that I have provided a tooth brush container which permits a thorough drying of the tooth brush within eight hours. Since the brush is seldom used at more than eight hour intervals, the container delivers a dry brush to the user. At the same time the brush is completely sterilized by the antiseptic materials which are provided in the container. The life of the brush is greatly prolonged because it is allowed to dry after each use and the user is protected from infection because the dried brush is thoroughly sterilized. It should be understood that while this invention has been described with particular reference to a tooth brush container that it is, nevertheless, useful for other purposes wherein it is desired to dry and sterilize a wet or moist article.

I am aware that many changes may be made and numerous details of construction may be varied through a wide range without departing from the principles of this invention and I, therefore, do not purpose limiting the patent granted hereon otherwise than necessitated by the prior art.

I claim as my invention:

1. A sterilizing receptacle for articles to be dried and sterilized comprising a container having porous walls of unglazed ceramic material permitting the passage of moisture therethrough and an antiseptic material in communication with the interior of said container.

2. A tooth brush receptacle comprising an elongated self-sustaining container adapted to receive the entire length of a tooth brush, means for closing said container, said container having integral moisture permeable walls of unglazed ceramic material and antiseptic material impregnated into said walls for creating a sterilizing atmosphere around the tooth brush.

3. A tooth brush receptacle comprising a tubular container having a bottom wall and a top enclosure member, this container being formed of porous unglazed porcelain, a relatively non-porous coating on part of the outside surface of said tube, said coating defining an uncoated portion to allow passage of moisture from the inside of the container to the outside atmosphere and an antiseptic material coated on the inside walls of said container.

4. A tooth brush receptacle comprising an elongated self-sustaining container adapted to receive the entire length of a tooth brush and means for closing said container, the walls of said container being formed of porous ceramic material permitting the passage of moisture therethrough, and having an antiseptic material distributed therein.

5. A tooth brush receptacle comprising a self-sustaining container having integral porous walls of unglazed porcelain impregnated with para formaldehyde.

6. A tooth brush container comprising an elongated tubular member adapted to receive the entire length of a tooth brush, said member having porous walls with an annular groove around the periphery thereof and a flattened portion extending longitudinally thereof, there being a coating of relatively non-porous material covering the outside surface of said walls except at the groove and flattened portion thereof, the inside walls of said member being impregnated with para formaldehyde.

MILTON THEO. HANKE.
